ELECTRIC SWITCH

Filed Feb. 9, 1927

Inventor:
John V. Schafer
By G. A. Bragg Atty

UNITED STATES PATENT OFFICE.

JOHN V. SCHAFER, OF BRONSON, MICHIGAN, ASSIGNOR TO HARRY A. DOUGLAS, OF BRONSON, MICHIGAN.

ELECTRIC SWITCH.

Application filed February 9, 1927. Serial No. 166,896.

My invention relates to electric switches and has for its object the provision of an improved contact member or members normally stationarily held with respect to a carrier therefor.

The device of my invention is inclusive of an electric current conducting contact arm having one end fixed upon a carrier and the other end adapted for engagement with a complementary contact. In accordance with one feature of the invention, the contact arm is made flexible and there is a spring interposed between it and the contact carrier whereby the contacting end of the arm is adapted to be pressed upon a complementary contact with desired force. The spring is not required to be included in the electric circuit so that its capacity is not reduced by current flowing therethrough.

In accordance with another feature of the invention, the mounted end of the contact arm has facility for fixed anchorage upon the carrier to have either of a plurality of directions whereby the contacting end of the arm may be adapted to differing locations of a complementary contact.

I will explain my invention more fully by reference to the accompanying drawing in which Fig. 1 is a sectional view of a combined ignition and lighting switch employing contacts arranged in accordance with my invention; Fig. 2 is a sectional view on line 2—2 of Fig. 1; Fig. 3 is a sectional view, on a larger scale, showing the preferred form of contact arm, a spring interposed between the contacting end of the arm and the contact carrier and a screw for connecting a circuit wire with the contact arm; Fig. 4 is a sectional view on line 4—4 of Fig. 1; and Fig. 5 is a perspective view of a portion of the contact carrier and one form of contact arm to be assembled therewith and shown separated therefrom.

The switching mechanism is enclosed within a casing which is inclusive of a front end wall 1 provided with a rearwardly projecting rim 2 having clips 3 thereon which clamp the body portion 4 of the casing against said end wall. The lock member 5 is tubular and carries prongs 6 that are clinched outwardly against the outer face of the end wall 1. Said lock member 5 projects rearwardly from the casing end wall into the casing and contains a rotatable tumbler barrel 7 in which are provided a number of

transversely movable tumblers 8 that are receivable in openings 9 formed in opposite sides of the lock member 5, the tumbler barrel 7 being held from rotation when the tumblers are in said openings. A suitably formed key serves to withdraw the tumblers from the openings 9 and may be turned following the withdrawal of the tumblers from said openings.

A contact actuator is provided at the inner end of the lock member 5, this actuator being inclusive of an insulating ring 10 which surrounds the inner end of the tumbler barrel and is in splined connection therewith, this end of the tumbler barrel 70 being oblong and entering the bore of the ring that is shaped correspondingly thereto, whereby the ring may be turned. This actuator is also inclusive of a metallic contact carrier 11 having radiating projections 12, 75 13 and 14 which constitute substantially rigid switch contacts. The rear end wall of the casing body 4 is shown as being of step formation, the rear end 4' of the casing body 80 being cylindrical and of shorter diameter than the front end of the casing body which is also cylindrical and is coaxial with the rear end of the casing. The switch contacts 15, 16 and 17 that are complementary to the contacts 12, 13 and 14 are in the nature of 85 cup formations upon the unmounted ends of the contact arms 18. These contact arms are desirably formed of flexible spring metal and integrally with the metallic sleeves 19 which pass through the insulating casing 90 body. These sleeves are provided with flanges 20 and 21 upon their ends, the casing body being snugly received between these flanges. The contact arms 18 project laterally from the flanges 21 of the metallic 95 sleeves 19, the contacts 15, 16 and 17 being integrally formed with said contact arms. These contacts are brought into electrical connection with circuit wires by means of the binding screws 22 which are threaded 100 into the interiors of the sleeves 19 and serve to secure said wires in firm mechanical and electrical connection with said sleeves. As indicated in Fig. 2, these circuit wires are connected with the generator, the induction 105 coil and battery. By suitably turning the tumbler barrel 7, the ignition circuit of an internal combustion engine having the switch described may be controlled, as is well understood by those skilled in the art. The 110

outer ends of coiled springs 23 enter the cavities of the contacts 15, 16 and 17, these cavities facing the casing body. The other ends of said springs are received in recesses 24 formed in the casing body. Said contact arms 18 are bent to space their contacting ends sufficiently from the casing body. As illustrated, the sleeves 19 which pertain to the contact arms 18 which carry the contacts 15, 16 and 17 are polygonal in their exterior contour, openings in said casing body being correspondingly shaped and receiving these particular sleeves that are prevented from turning with respect to the casing body. 10 The portion of the casing body which carries the switch arms 18 having the contacts 15, 16 and 17 thereon is, itself, a contact carrier, the invention not being limited to the employment of the casing body as a contact carrier. 15

The switch illustrated, is also adapted for the control of lighting circuits of an automobile or other automotive vehicle, said switch including a second contact actuator 25 which is surrounded by the front end of the casing body 4 and is inclusive of an insulating ring 25 and a contact carrier 26 in the form of a metallic ring, the ring 26 carrying substantially rigid switch contacts 27, 30 28, 29 and 30. The second contact actuator is operated by a handle 31 mounted to turn upon the exterior of the casing and having prongs 32 that pass through slots 33 formed in the casing end wall 1, these prongs entering openings 34 that constitute radial enlargements of the bore of the insulating ring 25, this ring and these prongs being in sliding engagement. The handle has flange formations 35 that are received between the 35 casing wall 1 and a plate 36, the hub 31' of the handle entering a central opening in this plate. The plate 36 is suitably assembled with the casing end wall as by means of rivets 37. The plate 36 may constitute a 40 mounting plate for the switch structure, as illustrated.

The switch contacts 38, 39, 40 and 41 that are complementary to the switch contacts 27, 28, 29 and 30 are also in the nature of cup formations carried upon contact arms 18' and 18², the openings in the cups facing the body 4. All of the contact arms 18, 18', 18² are of similar formation, the arms 18' being integrally formed with the inner flanges 21' upon the metallic sleeves 19' that are of hexagonal contour snugly received within corresponding openings in the insulating body of the casing which also serves as a carrier for the arms 18' and the contacts 50 thereon, the portion of the body 4 in the zone of the sleeves 19' constituting a contact carrying block. The other ends of the sleeves 19' are formed with flanges similar to the flange 20 so that the sleeves 19' are 55 firmly gripped in assembly with the casing

body. These sleeves 19' are interiorly threaded to receive binding screws 22'. The sleeves 19² which carry the arms 18² are circular in contour but are otherwise similar to the sleeves 19' and are similarly integrally formed with the arms 18² and similarly assembled with the insulating body of the switch casing. The contact arms 18', 18² are pressed upon by the coiled springs 23' which are contained within the recesses 24' formed in the casing body. These springs 70 press upon the contacts 38, 39, 40 and 41 outwardly from the portion of the casing body carrying these springs, functioning similarly in this respect to the springs 23. All of the 75 springs are so located as to carry no current so that their efficiency is not impaired by the passage of current therethrough. The latter contacts are variously connected with the wiring pertaining to the battery, the tail 80 lamp and the bright and dim head lamp circuits. By suitably turning the handle 31, the selected lamp circuits may be closed or all of these circuits may be opened. It is 85 obvious that these circuits may be rearranged or reduced in number. I have shown means whereby some of the contacts may be readily rearranged in rearranging the circuits. The contacts carried by the arms 18² are carried upon sleeves 19² that are cylindrical in contour. These arms may be swung 90 to different positions. I have shown extra recesses 24² which are spaced apart from the centers of the sleeves 19² similarly to the corresponding recesses 24'. The arms may be 95 swung over the recesses 24² and two of the springs 23' may be located in these latter recesses to function as they did before. I do not wish to be limited to the recesses 24² for the purpose of locating the springs. 100 Changes may be made without departing 105 from the invention.

Having thus described my invention, I claim:

1. In a switch structure, the combination 110 with a contact carrying block; of an interiorly threaded sleeve passing through said block and having flanges upon its ends which grip the block between them, one of said flanges having a lateral extension in the 115 form of a contact arm whose outer end is spaced apart from said block and is of cup formation, the open end of the cup formation facing said block; a coiled spring seated upon said block and entering said cup formation; and a binding screw screwed into said sleeve.

2. In a switch structure, the combination 120 with a contact carrying block; of an interiorly threaded sleeve passing through said block and having flanges upon its ends which grip the block between them, one of said flanges having a lateral extension in the 125 form of a contact arm whose outer end is spaced apart from said block and is of cup 130

formation, the open end of the cup formation facing said block; and a binding screw screwed into said sleeve.

3. In a switch structure, the combination 5 with a contact carrying block; of an interiorly threaded sleeve passing through said block and having flanges upon its ends which grip the block between them, one of said flanges having a lateral extension in the form 10 of a contact arm whose outer end is spaced apart from said block; and a binding screw screwed into said sleeve.

4. In a switch structure, the combination 15 with a contact carrying block; of an interiorly threaded sleeve passing through said block and having flanges upon its ends which grip the block between them, one of said flanges having a lateral extension in the form of a contact arm; and a binding 20 screw screwed into said sleeve.

5. In a switch structure, the combination 25 with a contact carrying block; of an interiorly threaded sleeve received in said block and having a flange at one end, this flange having a lateral extension in the form of a contact arm whose outer end is spaced apart 30

from said block and is of cup formation, the open end of the cup formation facing said block; a coiled spring seated upon said block and entering said cup formation; and a 35 binding screw screwed into said sleeve.

6. In a switch structure, the combination 40 with a contact carrying block; of an interiorly threaded sleeve received in said block and having a flange at one end, this flange 35 having a lateral extension in the form of a contact arm whose outer end is spaced apart from said block and is of cup formation, the open end of the cup formation facing said block; and a binding screw screwed into said 40

5. In a switch structure, the combination 45 with a contact carrying block; of an interiorly threaded sleeve received in said block and having a flange at one end, this flange having a lateral extension in the form of a contact arm whose outer end is of cup formation; and a binding screw screwed into said sleeve.

In witness whereof, I hereunto subscribe 50 my name.

JOHN V. SCHAFER.
